US0D1047247S

(12) **United States Design Patent** (10) **Patent No.:** **US D1,047,247 S**
(45) **Date of Patent:** **** Oct. 15, 2024**

(54) **LIGHTING UNIT**

(71) Applicant: **Eaton Intelligent Power Limited**,
Dublin (IE)

(72) Inventors: **Parthibhan Subramanian**, Soest (DE);
Jens Burmeister, Eberbach (DE)

(73) Assignee: **EATON INTELLIGENT POWER
LIMITED**, Dublin (IE)

(**) Term: **15 Years**

(21) Appl. No.: **29/771,585**

(22) Filed: **Feb. 24, 2021**

Related U.S. Application Data

(62) Division of application No. 29/712,737, filed on Nov. 11, 2019, now Pat. No. Des. 912,291, which is a division of application No. 29/684,840, filed on Mar. 25, 2019, now Pat. No. Des. 866,837, which is a division of application No. 29/612,017, filed on Jul. 27, 2017, now Pat. No. Des. 844,209.
